CUTTING BLADE

Original application filed November 10, 1928, Serial No. 318,327. Divided and this application filed October 31, 1931. Serial No. 572,396.

This invention relates to cutting blades and particularly to improvements in cutting edges of thin flexible razor blades.

An object of the present invention is to provide an improved cutting edge for blades such as razor blades, the intersecting surfaces of which are substantially flat or concaved directly up to the edge, the contour being continuous up to the cutting edge, and there being no portion of the intersecting surfaces forming the cutting edge that are convexly curved.

A feature of importance which enables the above object of the invention to be accomplished is that the cutting surfaces of the blade while being ground are maintained against any distortion due to pressure of the grinding element and are accurately ground in flat or slightly concaved form, the finishing operation applied to the edges serving to smooth and polish the surfaces immediately adjacent the cutting edge while preserving the contour to which these surfaces have been ground.

With these and other objects in view our invention consists in the features of construction and operation set forth in the following specification and illustrated in the accompanying drawing.

In the accompanying drawing annexed hereto and forming a part of this specification, we have shown our invention embodied in a thin, flexible, double-edged razor blade, but it will be understood that the invention can be otherwise embodied and that the drawing is not to be construed as defining or limiting the scope of the invention, the claims appended to this specification being relied upon for that purpose.

In the drawing:

Figure 1 is a conventional form of cutting blade which may have cutting edges thereon of the type described and claimed in this application.

Fig. 2 is a cross sectional view, greatly magnified, of a small portion of the present improved blade adjacent its edge after being ground.

Fig. 3 is a view similar to Fig. 2 showing portions adjacent an edge of the present im-

proved type of blade after having been completely finished.

Fig. 4 is a diagrammatic view of a device by means of which the improved edges may be ground.

Fig. 5 is a cross-sectional view of a portion of the improved cutting edge greatly magnified and shown superposed over a corresponding portion of a conventional blade of the prior art, both cutting edges being shown immediately after the grinding operation.

Fig. 6 is a view similar to Fig. 5 of a portion of applicants' cutting edge after grinding and shown superposed over a similar portion of a prior art blade, both cutting edges being shown ready for the final finishing operation, and

Fig. 7 is a view, magnified similarly to Fig. 2, and showing a finished blade of conventional or prior art form.

In the above drawing we have shown a preferred form of the invention and a method by which it may be ground, but it will be understood that changes and modifications may be made within the scope of the appended claims without departing from the spirit of the invention.

Briefly and in its broadest aspect our invention may include a blade having its cutting surfaces characterized by being flat or concave as distinguished from convex immediately adjacent the cutting edge, the contours of the cutting surfaces as ground being preserved in the finished blade.

Referring more in detail to the figures of the drawing, we show a blade 10 of conventional thin and flexible form which may have its cutting edges formed according to the present invention. The process and device preferably made use of in the production of the present cutting edges are shown in our copending applications 318,327 and 417,051 filed November 10, 1928 and December 28, 1929 respectively. This present application forms a division of application 318,327.

The surfaces forming the cutting edge of the blade 10 are ground to the form shown by the lines 11—11, the method of grinding one of these surfaces being shown diagrammatically in Fig. 4. The blade 10 during the

grinding operation is supported by a rigid member 12 closely fitting the side opposite that being ground and extending up to and beyond the cutting edge. The wheel 13 effecting the grinding is advanced against the blade 10 while thus supported and in grinding the surface of the blade 10 opposite that supported by the surface of supporting member 12 cuts away a small portion of the support 12 closely adjacent the cutting edge being formed. By being thus supported up to its cutting edge while being ground the cutting edge is formed as shown, greatly magnified, in Fig. 2, the surfaces forming the cutting edge being undistorted during the grinding operation, due to its being completely supported and consequently retaining a slightly concave form. The finishing operation of the blade 10, usually honing and stropping, requires only to smooth and polish the areas of the cutting surfaces 11 immediately along the edge. This reduced amount of finishing operation required is due to the absence of a fin edge 14 as shown in Fig. 5 formed along the ground edge by the conventional grinding operation and as indicated in Fig. 5.

In finishing blades of the prior art type such as shown by the outer contours 16 in Figs. 5 and 6, after the grinding operation the first effect is to break away the fin extension 14 formed during grinding, leaving a rounded blunt edge as shown in the outer contour in Fig. 6. The finishing of these prior art blades therefore must be continued until the blunted edge, the thickness of which corresponds to the thickness of the fin 14 is sharpened to a keen edge. In accomplishing this finishing of a relatively blunt edge as by honing the effect is to form convex surfaces adjacent the edges as indicated in Fig. 7 in magnified form similar to Figs. 5 and 6. It is primarily in the elimination of this convex form of the cutting surfaces immediately adjacent the cutting edge that characterizes the present improved blade.

The thickness of the fin 14 formed by the conventional grinding and shown in magnified form in Fig. 5 is a definite and material amount and represents the width of the blunted edge shown in Fig. 6. This thickness must be eliminated and determines the amount of finishing such as honing or stropping necessary to give the blade a sharp edge. By forming the cutting surfaces of the improved edge by the grinding operation as represented diagrammatically in Fig. 4 wherein no fin is produced and thus eliminating the necessity of finishing a blunt edge, what finishing is necessary for the improved blades amounts only to smoothing the surfaces to eliminate the scratches formed in grinding by the abrasive material used. The edge as indicated in Fig. 3 remains after finishing with its cutting surfaces substantially unchanged, retaining their substantially flat, or slightly concave

form, the intersecting angle being slightly but not materially increased. The continuously curved form of the cutting surfaces formed by the grinding operation are maintained without distortion during the finishing operation.

What we claim is:

1. As an article of manufacture, a blade having a cutting edge having slightly concave marginal faces, characterized by the fact that said faces are substantially flat in the immediate proximity of said edge as distinguished from convex due to the absolute absence of any deformations occurring adjacent the edge during the edge forming and finishing treatment. 70

2. As an article of manufacture, a blade having a cutting edge having two intersecting ground faces inclined to each other and characterized by the fact that at least one of said faces is of uniform concave form throughout its area adjacent said edge. 75

3. As an article of manufacture, a thin flexible razor blade having a cutting edge having two intersecting ground faces inclined to each other and characterized by the fact that at least one of said faces is of uniform curvature throughout its area adjacent the cutting edge. 90

4. As an article of manufacture, a thin flexible razor blade having a cutting edge having two intersecting ground faces inclined to each other and characterized by the fact that said faces are of uniform curvature throughout their area adjacent the cutting edge. 95

In testimony whereof, we hereto affix our signatures

MAX MAAG.
